Application December 31, 1949, Serial No. 136,376

4 Claims. (Cl. 74—527)

1

This invention relates to electric switch mechanisms and, more particularly, to an improved positioning mechanism for positioning a movable member such as the movable contact member of an electric switch of the coaxial type.

In the operation of a coaxial switch it is very important that when the movable contact means is moved to an engaged switch position it assume an accurately aligned relation with respect to the stationary contact means engaged thereby. The present invention is especially concerned with an actuating means for the movable switch member or rotor of such a coaxial switch and provides novel positioning means by which such an accurately aligned relation will be automatically obtained during each movement of the movable contact means to its engaged switch position.

In a coaxial switch mechanism of the type in which the movable contact means, or the rotor carrying the same, is actuated by a power means such as an electromagnetic device, the need for such a positioning means is even more imperative because the momentum of the moving parts and the irregularities or variations inherent in the functioning of the power device prevent the movable contact means from regularly assuming an accurately aligned position relative to the stationary contact means engaged thereby.

The present invention accordingly provides novel positioning means which is effective for locating a movable switch member or the like during the shifting thereof to an engaged switch position, such that the movable contact means will always assume an accurately aligned relation with respect to the stationary contact means engaged thereby.

As another object thereof this invention provides novel positioning mechanism for a movable switch member or the like in which a holding member cooperating with a toothed member is a pivoted lever and an eccentric adjusting means is effective on such lever for adjusting or setting the positioning means so that it will cause the desired accurate alignment of the movable and stationary contact means.

The invention can be further briefly summarized as consisting in certain novel combinations and arrangements of parts hereinafter described and particularly set out in the claims hereof.

In the accompanying sheets of drawings,

Fig. 1 is a longitudinal section taken through a coaxial switch mechanism embodying the present invention;

2

Fig. 2 is an outside end view of the mechanism looking toward the coaxial switch;

Fig. 3 is a transverse section taken through the mechanism adjacent the outer end of the electromagnetic power device as indicated by section line 3—3 of Fig. 1;

Fig. 4 is a transverse section taken at a point between the power device and the coaxial switch as indicated by section line 4—4 of Fig. 1;

Fig. 5 is a fragmentary sectional view taken longitudinally through one of the pivoted levers of the positioning means substantially as indicated by section line 5—5 of Fig. 4;

Fig. 6 is another fragmentary sectional view taken through the eccentric adjusting means of the pivot levers substantially as indicated by section line 6—6 of Fig. 5;

Fig. 7 is a transverse section taken through the power device adjacent the ratchet mechanism thereof, as indicated by section line 7—7 of Fig. 1;

Fig. 8 is a partial transverse section taken through the power device substantially at the location of the ratchet mechanism thereof, as indicated by section line 8—8 of Fig. 1;

Fig. 9 is a partial transverse section taken through the power device adjacent the indexing switch means thereof, as indicated by section line 9—9 of Fig. 1;

Fig. 10 is a fragmentary sectional view of the coaxial switch corresponding with a portion of the longitudinal section of Fig. 1, but showing a sighting device substituted for one of the stationary contact carriers;

Fig. 11 is another fragmentary sectional view taken through the coaxial switch substantially as indicated by section line 11—11 of Fig. 10 and further illustrating the sighting device; and

Fig. 12 is a perspective view showing a shaft coupling member in detached relation.

As shown in the drawings, the improved coaxial switch mechanism 10 comprises, in general, a coaxial switch 11 and a switch actuating mechanism 12 operably connected with such coaxial switch. The coaxial switch 11 is more fully disclosed in related copending application Serial No. 780,059, filed October 15, 1947 now Patent No. 2,565,643, granted August 28, 1951.

The coaxial switch 11 is of the type comprising a switch housing 13 formed of connected sections defining a switch chamber 14, and a rotor 15 substantially filling said chamber and operable therein. This coaxial switch also includes a plurality of arcuately spaced stationary switch contacts 16, in this instance three such stationary

contacts, which extend into the switch chamber and engage a circumferential flange 17 carried by the rotor 15. Each of the stationary contacts 16 is mounted in coaxial relation in a carrier 18 by a body of electrically insulating plastic material 19 contained therein. The carrier 18 is mounted on the housing 13 so as to have a snug fitting engagement in a socket opening 20 of the latter and locates the contact 16 in proper position for running engagement with the rotor flange 17.

The rotor 15 of the coaxial switch 11 carries a movable contact 21 which is formed by the end of a conductor 22 and is located in an interruption or gap 23 of the rotor flange 17. The conductor 22 is coaxially mounted in a passage 24 of the rotor by a body of plastic insulating material 25 contained in such passage. The conductor 22 extends into the rotor radially and axially thereof from the contact 21 and its outer end projects from the rotor as a reduced pin 26 which is rotatable in a stationary contact member 27 mounted in a carrier 28.

The contact 21 is of the same thickness as the rotor flange 17 and forms a smooth, flush continuation of this flange. The portions of the gap 23 are closed on opposite sides of the contact 21 by portions 29 of the insulating body 25 so that these insulating portions also form smooth, flush continuations of the rotor flange. The stationary contact 27 forms a receiving terminal to which electrical signals are delivered and the stationary contacts 16 form delivery terminals. By movement of the rotor 15 the contact 21 can be shifted to an engaged switch position in engagement with any desired one of the stationary contacts 16. The rotor 15 is provided with a shaft extension 39 which projects from the housing 11 and to which actuating torque can be applied for driving the rotor. When the rotor contact 21 has been engaged with a desired one of the stationary contacts 16 it is necessary for the proper functioning of the coaxial switch 11, as mentioned above, that the rotor contact be accurately aligned or oppositely positioned with respect to the stationary contact so engaged. The present invention provides novel positioning means for obtaining this accurate alignment and which positioning means will be described in detail hereinafter.

The switch actuating mechanism 12 includes an outer housing 31 formed by complementary cup-shaped housing sections 31a and 31b. The housing section 31a is connected with the switch housing 13 by a pair of posts 32 having threaded ends 32a which are screwed into the switch housing for clamping the housing member 31a thereagainst with a gasket 33 interposed therebetween. The housing section 31a forms the base of the outer housing and the housing section 31b forms a cover which is held in assembled relation to the base by a group of tie rods 34. As shown in Fig. 1, the adjacent ends of the housing sections 31a and 31b engage in oppositely extending grooves of a sealing ring 35.

Also included in the switch actuating mechanism 12 is an electromagnetic power device 38 having an intermittently rotatable power output shaft 39. This electromagnetic power device is a so-called rotary solenoid of the kind forming a part of the mechanism disclosed in U. S. Patent No. 2,430,940, granted November 18, 1947. The power device 38 also includes a magnet coil 40 located in a casing 41 and an axially movable armature 42 connected with a rotary shaft 43.

75 58 are adapted to be opened by an actuating

which is axially aligned with the power output shaft 39. The armature 42 is movable toward and away from a core 44 which is also located in the casing 41 and is adapted to be magnetized by the coil 40.

At its outer end the armature 42 is connected with a plate 45 which is disposed in spaced relation to the end wall 46 of the casing 41. The adjacent faces of the plate 45 and the end wall 46 are provided, respectively, with shallow arcuate recesses 47 and 48 located in overlapping relation to each other and forming a pocket in which an antifriction ball 49 is confined. Three groups of the paired arcuate recesses 47 and 48 are provided and, as shown in Fig. 3, these paired recesses are disposed in circumferentially spaced relation around the axis of the rotary shaft 43. A spiral spring 50 disposed around the shaft 43 and having one of its ends anchored thereon transmits thrust through the shaft to the armature 42 normally urging the same toward the left, as seen in Fig. 1, or, in other words, away from the core 44.

When the coil 40 is electrically energized, the magnetic pull on the armature 42 stresses and overcomes the spring 50 and moves the armature toward the core, that is, toward the right as seen in Fig. 1. During this movement of the armature 42, the plate 45 travels in an axial direction from its dotted line position to its full line position and the thrust applied to the balls 49 by this axial movement causes the plate to rotate through the limited arcuate movement represented by the permissible travel of the balls in the paired arcuate recesses 47 and 48. This combined rotary and axial movement of the plate 45 causes a corresponding combined rotary and axial movement of the shaft 43.

The adjacent ends of the shafts 43 and 39 are operably connected by a ratchet mechanism formed by a pair of cooperating plate members 51 and 52 mounted on these shafts. These plate members carry groups of circumferentially spaced inclined fingers 53 and 54 which are deflected toward each other out of the planes of the respective plate members. During the combined rotary and axial movement of the shaft 43 a similar combined rotary and axial movement is imparted to the plate member 51, causing one of the fingers 53 thereof to engage one of the fingers 54 of the plate member 52 and impart rotary movement to the latter plate member and to the shaft 39 connected therewith. Thus, during each such combined rotary and axial power stroke of the shaft 43, one of the fingers 53 of the plate member 51 engages and drives one of the fingers 54 of the plate member 52 and successive power strokes of the shaft 43 impart a step-by-step rotary movement to the shaft 39. During the retractive movement imparted to the shaft 43 in the opposite direction by the spiral spring 50, the plate member 51 is rotated in the reverse direction thereby disengaging the finger 53 from the finger 54 and causing the plate member 51 to have a rotary ratchet movement with respect to the plate member 52.

The power device 38 also includes two switch devices 56 and 57 for intermittently energizing and deenergizing the magnet winding 40 and which switch devices are in a series relation in the energizing circuit for this winding. The switch device 56 comprises a pair of normally closed contacts 58, one of which is a movable contact carried by a spring arm 56a. The contacts

finger 59 of a plate member 60 which is formed of insulating material and is rotatable about the shaft 39. The switch actuating member 60 is adapted to be oscillated by movement transmitted thereto from the plate member 51. For this purpose, the plate member 51 carries an axially extending finger 61 which extends between the finger 59 of the plate member 60 and an adjacent finger 62.

When rotary movement in the clockwise direction indicated in Fig. 8 is imparted to the plate member 60 by the above-mentioned axial finger 61 of the plate member 51, the radial finger 59 will engage the portion 56b of the spring arm 56a and will deflect this spring arm to cause opening of the contacts 58. Since these contacts are in the circuit of the magnetic coil 40, the opening thereof will temporarily deenergize the magnet and permit the spiral spring 50 to retract the armature 42. As mentioned above, a reverse rotary movement is imparted to the plate member 51 by the spiral spring 50 during the retraction of the armature 42 and, by means of the axial finger 61, this causes the switch actuating member 60 to be shifted in the opposite direction, that is in a counter-clockwise direction as seen in Fig. 8, to disengage the radial finger 59 from the spring arm 56a and permit reclosing of the contacts 58 by this spring arm for reenergizing the magnet coil 40. The closing and opening of the switch 58 causes the magnet 40 to be repeatedly energized to operate the ratchet drive formed by the cooperating plate members 51 and 52 to thereby impart a step-by-step clockwise rotation to the output shaft 39.

The energizing circuit for the magnet coil 40 is also controlled by the switch device 57 which comprises a flat ring 63 of conducting material connected with the shaft 39 so as to be driven thereby through an insulating disk 64. The switch device 57 also includes a number of contacts 65 mounted on an insulating support 66 and having sliding engagement with the contact ring 63. As shown in Fig. 9, the contact ring 63 has a gap or interrupting recess 67 therein which passes under the contacts 65 in succession during the rotation of this contact ring by the shaft 39.

The energizing current for the magnet 40 passes through the contact ring 63 and a selected one of the contacts 65. So long as the energization of the magnet coil 40 is interrupted only by the self-closing switch device 56, the power device 38 will operate to drive the rotor output shaft 39 with a step-by-step angular movement. When the gap 67 of the contact ring 63 arrives at the contact which is then included in the magnet energizing circuit, such as the contact 65a, the circuit will be broken and the magnet will remain deenergized regardless of the reclosing of the contacts 58 of the switch device 56.

The outer end of the power output shaft 39 of the power device 38 is connected with the shaft extension 30 of the rotor 15 of the coaxial switch 11 and the operation of the power device imparts a similar step-by-step rotary movement to the rotor. In the coaxial switch 11 here shown the stationary contacts 16 are spaced apart an angular distance of one hundred and twenty degrees, and in the construction here shown for the power device 38 each energization of the magnet 40 causes the shaft 39 to be rotated through an angular distance of thirty degrees which bears a modular relation to the one hundred and twenty degrees spacing of the stationary contacts 16 of the coaxial switch. The magnet 40 of the power 75

device 38 is energized through a selected one of the contacts 65 of the switch device 57, such as the contact 65a, which will result in operation of the power device continuously until the rotor contact 21 reaches the stationary contact 16 desired to be engaged for the signal circuit to be completed, whereupon the gap 67 of the contact ring 63 will arrive at a position under the selected contact 65a to deenergize the circuit of the magnet coil 40, thereby leaving the rotor contact 21 in engagement with the desired stationary contact 16.

As has already been indicated above, it is important in the operation of the coaxial switch 11 that the rotor contact 21 be accurately aligned with the stationary contact 16 which is engaged thereby. To this end the present invention provides a positioning means 70 which is effective for locating the rotor contact 21 in such accurately aligned relation with respect to the stationary contact 16 engaged thereby. The positioning means 70 comprises a wheel 71 having a hub 72 and such wheel being mounted on the shaft extension 30 of the rotor 15 by means of the transverse pin 73. The wheel 71 has a circumferential series of spaced teeth 74 thereon and each pair of adjacent teeth provide therebetween a locating recess 75. The positioning means 70 also includes a pair of levers 76 located on opposite sides of the wheel 71 and each of which carries an antifriction roller 77.

The rollers 77 of the levers 76 are engageable in a pair of recesses of the wheel 71 at substantially diametrically opposite points thereof and the rollers are urged into the recess of the wheel by tension springs 78 acting on the arms. The levers 76 are preferably of a hollow construction, as shown in Fig. 5, and the antifriction roller 77 comprises a ball bearing located in the hollow lever and mounted on a shaft formed by a pin 79 extending through the spaced arms of the lever. Inwardly deflected portions 80 of the arms of the lever extend around the pin 79 and engage the inner race 81 for positioning the ball bearing substantially midway between the spaced arms. The outer race 82 of the ball bearing is thus held out of rubbing contact with the arms of the lever and forms the rim portion of the antifriction roller 77 which engages in one of the recesses 75 of the toothed wheel 71.

A pair of posts 83 having threaded ends connected with the switch housing 13 extend in substantially parallel relation to the posts 32 and to the axis of the shaft extension 30 and provide a mounting means for pivotally mounting the levers 76. This mounting means will be presently described in greater detail.

From the construction of the positioning means 70 as thus far described, it will be seen that the wheel 71 constitutes a reaction member which is connected with the rotor 15 and each of the levers 76 constitutes a holding member which cooperates with this reaction member. The wheel 71 is provided with twelve of the recesses 75 and, hence, these recesses are spaced apart an angular distance of thirty degrees, which bears the same modular relation to the spacing of the stationary contacts 16 of the coaxial switch 11 as the increments of angular movement imparted to the power output shaft 39 by the power device 38. When the rotor 15 is driven by the power device 38, the wheel 71 is rotated and the antifriction rollers 77 of the levers 76 ride over the tops of the teeth 74, there-

by passing from one to another of the recesses 75 of this wheel.

When the rotor contact 21 arrives at the selected stationary contact 16 and the magnet 40 of the power device 38 is deenergized by the switch device 57 to leave the rotor contact in engagement with such stationary contact, the antifriction rollers of the levers 76 will then be engaged in a pair of diametrically opposite recesses of the wheel 71. This engagement accomplishes an important purpose in that as the rollers are urged into the recesses by the tension springs 78, the wheel 71 functions as a reaction member and the engaged recesses thereof center themselves with respect to the antifriction rollers engaging therein. This self-centering of the recesses 75 of the wheel 71 with respect to the rollers 77 reacts through the wheel and the shaft extension 30 to position the rotor 15 with the rotor contact 21 in accurately aligned relation to the stationary contact 16 engaged thereby.

Because of the antifriction characteristic of the rollers 77, they will be very effective under the influence of the springs 78 in producing a powerful self-centering action of the wheel 71. In this connection it is also important to note that the size and shape of the teeth 74 with respect to the size and shape of the roller 77 is such that the recess 75 will have a shape and depth causing the rim of the roller to engage the pair of adjacent teeth at points near the tops thereof. These points of engagement are thus located at the maximum distance from the axis of rotation and this contributes to the application of a self-centering force of maximum magnitude on the wheel 71. Since the shape thus provided for the recess 75 is such as to prevent the roller 77 from engaging the bottom of the recess, it will also be seen that this desired engagement of the roller with the pair of teeth adjacent the ends thereof will always be maintained and will enable the levers 76 to serve as a holding means for maintaining the rotor contact 21 in the aligned relation with respect to the stationary contact 16 engaged thereby.

Another important feature of this novel positioning mechanism is the provision of an adjusting means which is embodied in and effective on the positioning means 70. This adjusting means is incorporated in the pivotal mountings for the levers 76. As shown in Figs. 5 and 6, the reduced end portion 84 of each of the posts 83 provides a pivot shaft for the lever 76 associated therewith. The lever is not pivoted directly on the shaft 34 but is connected therewith through an adjusting means in the form of an eccentric bushing 85 interposed between the shaft and the sleeve portion 86 of the lever. A spacing washer 87 also disposed around the shaft 84 holds the lever 76 in spaced relation to the bottom wall 88 of the housing section 31a.

The eccentric bushing 85 is provided at one end thereof with a head 89 of a non-circular shape, preferably hexagonal, as here shown, and by which this bushing can be rotatably adjusted on the pivot shaft 84 by means of a suitable wrench. A shoulder 90 provided on the post 83 adjacent the pivot shaft portion 84 thereof cooperates with the head of the eccentric bushing for applying a clamping force to the bushing and the spacing washer 87. The sleeve portion of the bushing is somewhat longer than the sleeve portion 86 of the lever 76 so that when the bushing is clamped in the desired position of angular

adjustment, the lever 76 will still be free to swing pivotally on the eccentric bushing.

The adjusting means provided by the eccentric bushing 85 affords a means by which the rotor contact 21 can be shifted to the extent necessary to align the same accurately with the stationary contact 16 after the rotor contact has been moved into engagement with such stationary contact. In making this adjustment the post 83 is unscrewed relative to the switch housing 13 to release the clamping engagement of the shoulder 90 on the head 89 of the bushing 85 and then by a wrench applied to the head 89 the eccentric bushing 85 is rotated on the pivot shaft 84, causing lever 76 to be shifted longitudinally thereof. This longitudinal movement of the lever moves the roller 77 toward or away from the pivot shaft 84, depending upon the direction in which the eccentric bushing has been rotated, and this shifting of the roller imparts a corresponding rotary movement to the wheel 71 and to the switch rotor 15. When this adjusting operation has resulted in the rotor contact 21 being accurately aligned with the stationary switch contact 16, the post 83 is rotated in a direction to tighten its screw-thread connection with the switch housing 13 to thereby clamp the eccentric bushing 85 between the shoulder 90 and the spacing washers 87 and lock the bushing in its adjusted setting.

To facilitate the accomplishment of this adjusting operation, the invention provides a sighting device 92 shown in Figs. 10 and 11 and which is used as a reference means with respect to which the rotor contact 21 is shifted by the adjusting movement just described above. This sighting device comprises a cup-shaped member or bushing which is interchangeable with any one of the stationary contact carriers 18 of the switch housing 13. When the stationary contact carrier 18 has been detached from the switch housing 13, the sighting device 92 will be snugly received in the housing opening 20 and in Figs. 10 and 11 the sighting device is shown in its operative position engaged in such housing opening.

The sighting device 92 has a transverse wall 93 at its inner end and is also provided with a main axial opening or recess 94 extending thereinto and which includes a convergently tapered portion 94a at such end wall. On the axis of the recess 94 a circular sighting opening or orifice 95 is provided and extends through the end wall 93. The sighting orifice 95 has a diameter or plan dimension which is exactly equal to the diameter of the conductor 22 and hence is exactly equal to the plan dimension of the conductor 21 extending in the direction of the curvature of the switch rotor 15.

While the adjustment of the eccentric bushing 85 is being made, as explained above, the operator looks into the recess 94 of the sighting device 92 and observes the end of the rotor contact 21 through the sighting orifice 95 and thus uses the orifice as a reference means for determining when the rotor contact has been adjusted to a position which will provide an accurate alignment of this contact with the stationary contact 16. When this accurate alignment has been obtained and the adjusting bushing 85 has been reclamped in its locked position, the sighting device 92 is removed and the contact carrier 18 is replaced in the housing opening 20.

This invention also provides novel mounting means for the electromagnetic power device 38 by which this device can be firmly connected with the switch housing 13. This mounting

means comprises a plate member 96 which is connected with the casing 41 of the power device and projects laterally therefrom so as to provide mounting portions 96a lying in a transverse plane disposed in substantially normal relation to the axis of the power output shaft 39. The mounting portions 96a are here shown as being the corner portions of a substantially square shape for the plate member 96 and are provided with openings 98b which receive the reduced and threaded upper ends of the posts 32 and 83. When the power device 38 has been inserted into the outer housing 31 of the switch mechanism and the ends of the post engaged in the openings 96b of the mounting plate 96, the power device will be located with its power output shaft 39 in properly aligned relation with respect to the shaft extension 30 of the switch rotor 15. The posts 32 and 83 have shoulders 97 thereon against which the mounting portions 96a of the plate are clamped by the nuts 98 applied to the threaded ends of these posts.

With respect to the driving connection between the power output shaft 39 of the power device 38 and the shaft extension 30 of the switch rotor 15, this invention also provides a novel construction. As shown in Fig. 1, the power output shaft 39 is of a length such that it will project into the hollow hub 72 of the toothed wheel 71 when the power device 38 has been assembled in its proper position on the mounting posts 32 and 83, as explained above. The outer end of the power output shaft 39 preferably does not engage the shaft extension 30 directly but is connected therewith by a flexible coupling means which is substantially universally flexible. This coupling means is shown in this instance as comprising a coupling member 99 (see Figs. 1, 4, 5 and 12) having a tongue portion 100 on the inner end thereof which engages in a corresponding transverse slot provided in the end of the shaft extension 30 and at its other end the coupling member is provided with a pair of spaced axial arms 101 which embrace the outer end of the power output shaft 39 and define a transverse slot 102 in which a flattened end portion of the power output shaft is received. Since the coupling member 99 is partially housed in the opening of the hub 72 it will always be maintained in assembled relation with respect to the ends of the shafts 30 and 39 connected thereby. The opening of the hub 72 is of a size to provide a small clearance around the coupling member 99 so that this member will be capable of limited shifting in two directions for correcting small misalignments of the shafts 30 and 39.

As shown in Fig. 1, one of the mounting posts 83 is provided at its outer end with an extension post member 103 instead of one of the clamping nuts 98, and this extension post member provides a mount on which a condenser 104 can be mounted by means of a clamping bracket 105. The section 31b of the outer housing 31 is shown in Fig. 1 as being provided with an electric coupling member 106 with which the various electrical conductors serving the power device 38 can be connected and which provides a terminal means for electrically connecting the switch actuating mechanism with external circuit conductors.

From the foregoing description and the accompanying drawings it will now be readily understood that this invention provides novel positioning mechanism for use in indexing or locating a movable member in predetermined desired positions or settings, such as the movable switch

member of a coaxial switch, or the like. Additionally, it will be seen that this invention provides eccentric adjusting means in such a positioning mechanism for calibrating the location of the pivot axis of the holding lever means with respect to the predetermined positions to which the movable member is shiftable.

Although the novel positioning mechanism has been illustrated and described herein to a detailed extent, it will be understood, of course, that the invention is not to be regarded as being limited correspondingly in scope but includes all changes and modifications coming within the terms of the claims hereof.

Having thus described my invention, I claim:

1. In a positioning mechanism for an electric switch or the like, a housing structure, drive shaft means rotatable in said housing structure, a member in said housing structure and connected with said shaft means to be moved by the latter to predetermined positions, a wheel connected with said shaft means for rotation therewith and having thereon an annular series of teeth with intervening spaces between pairs of adjacent teeth, a lever having roller means engageable in any one of said spaces for holding cooperation with said wheel, spring means acting on said lever to urge said roller means into one of said spaces, pivot means mounting said lever for swinging movement, and eccentric adjusting means effective on said lever through said pivot means for calibrating the location of the effective axis of said pivot means with respect to said predetermined positions.
2. In a positioning mechanism for an electric switch or the like, a housing structure, drive shaft means rotatable in said housing structure, a member in said housing structure and connected with said shaft means to be moved by the latter to predetermined positions, a wheel connected with said shaft means for rotation therewith and having thereon an annular series of teeth with intervening spaces between pairs of adjacent teeth, a lever having roller means engageable in any one of said spaces for holding cooperation with said wheel, spring means acting on said lever to urge said roller means into one of said spaces, said lever having an opening therein at a point spaced from said roller means, a pivot shaft, and eccentric means carried by said pivot shaft and engaging in said lever opening for calibrating the location of the effective fulcrum axis of said lever with respect to said predetermined positions.
3. In a positioning mechanism for an electric switch or the like, a housing structure, drive shaft means rotatable in said housing structure, a member in said housing structure and connected with said shaft means to be moved by the latter to predetermined positions, a wheel connected with said shaft means for rotation therewith and having thereon an annular series of teeth with intervening spaces between pairs of adjacent teeth, a lever having roller means engageable in any one of said spaces for holding cooperation with said wheel, spring means acting on said lever to urge said roller means into one of said spaces, said lever having an opening therein at a point spaced from said roller means, a pivot shaft extending into the lever opening, and eccentric bushing means mounted on said pivot shaft and rotatable in said lever opening for calibrating the location of the effective pivot axis of said lever with respect to said predetermined positions.
4. In a positioning mechanism for an electric switch or the like, a housing, a rotary power de-

vice, shaft means rotatable relative to said housing and connected with said power device to be driven thereby, a member in said housing and connected with said shaft means to be moved by the latter to predetermined positions, a plurality of posts having reduced end portions connected with said housing, said posts extending in the direction of the axis of said shaft means and forming a mount for said power device, a wheel connected with said shaft means to be driven thereby and having an annular series of teeth with intervening spaces between pairs of adjacent teeth, a pair of levers located on opposite sides of said wheel and each having a roller thereon and an opening therein at a point spaced from the roller, said levers, being disposed with said reduced end portions extending through the lever openings as pivot pins and said rollers being engageable in said spaces for holding cooperation with said wheel, spring means acting on said levers for urging said rollers into said spaces, and eccentric adjusting bushings mounted on said pivot pins and engaging in the openings of said levers for calibrating the location of the effective fulcrum axes of said levers with respect to said predetermined positions.
